(57) **CLAIM**

The ornamental design for a vehicular ramp, as shown and described.

DESCRIPTION

FIG. 1 is a perspective of a vehicular ramp showing our new design;

FIG. 2 is a top view of the vehicular ramp;

FIG. 3 is a side view of the vehicular ramp;

FIG. 4 is a front view of the vehicular ramp;

FIG. 5 is a rear view of the vehicular ramp;

FIG. 6 is a bottom view of the vehicular ramp;

FIG. 7 is a view of the section of the vehicular ramp marked as 7—7 in FIG. 2;

FIG. 8 is a view of the section of the vehicular ramp marked as 8—8 in FIG. 2;

FIG. 9 is a view of the section of the vehicular ramp marked as 9—9 in FIG. 2;

FIG. 10 is a view of the section of the vehicular ramp marked as 10—10 in FIG. 4; and,

FIG. 11 is a view of the section of the vehicular ramp marked as 11—11 in FIG. 5.

The broken line showing of the rest of the body of a ramp is included for the purpose of illustrating environment and forms no part of the claimed design.
